UNITED STATES PATENT OFFICE

ROBERT H. BEAUMONT, OF RADNOR, PENNSYLVANIA, ASSIGNOR TO R. H. BEAUMONT CO., OF PHILADELPHIA, PENNSYLVANIA, A CORPORATION OF PENNSYLVANIA

SKIP-BUCKET DISCHARGE MECHANISM

Application filed April 6, 1928. Serial No. 267,871.

This invention relates to apparatus useful in hoisting material such as sand, gravel, coal, ashes, etc., and more particularly to that type known as skip-bucket mechanism 5 adapted to elevate material to a desired level for gravity dumping.

More specifically, the present invention relates to certain improvements in apparatus of the type described in my co-pending 10 application Serial Number 106,600, filed the 4th day of May, 1926; now matured into Patent No. 1,707,197, dated March 26, 1929; and, it has for a general object the provision of an inexpensive skip-bucket 15 discharge mechanism embodying novel means for moving the bucket into dumping position.

Other objects and advantages will be apparent from the following detailed explanation 20 of a typical embodiment of this invention, as illustrated by the accompanying drawings; while the alleged features of novelty are specifically defined in the subjoined claims.

25 In the drawings:—

Fig. I is a side elevation of a fragmentary portion of a skip-bucket discharge mechanism in accordance with the present invention; and,

30 Fig. II is a section, taken approximately as indicated by the line II—II in the preceding view.

Referring more in detail to the drawings a conventional skip-bucket is comprehensively 35 designated by the numeral 3; the same having a sloping mouth 4 and being constructed of sheet metal with appropriate bracings to give the requisite strength and rigidity. This skip-bucket 3 is adapted to a vertical (or inclined) track 5 conveniently though not essentially—of I-beams, or any other standard sections that will afford guidance for single or double flanged 40 pairs of wheels 6, 7. These upper and lower pairs of wheels 6, 7, respectively, are mounted on common axes 8, 9, supported by bearings 10 rigidly secured to one side of the skip-bucket 3; and they are of a size 45 to freely traverse the opposed inwardly-di-

rected lateral-flanges of the I-beams, aforesaid.

The skip-bucket 3 is supported and actuated through the medium of appropriate hoisting gear—not shown—attached centrally to a shaft 11, intermediate bail members 12, in turn pivoted at 13 to suitable pintles or bearing axes 14 rigidly secured to the bottom of said skip-bucket. Mounted at the outer ends of the shaft 11 are wheels 15 (complements of those designated 6 and 7) adapted to the track 5, while limit straps or stops 16 are secured to the skip-bucket 3, with their free ends suitably angled for engagement by the bail members 12, when the skip-bucket is in dumping position, as indicated by the dot-and-dash line showing in Fig. I, as well as serving to prevent overturning thereof.

At the back, the track 5 is provided with spaced upper and lower supports 17, 18, conveniently of angle-sections braced to said tracks by suitable sections 19. These supports 17, 18 it will be observed are rectangular in configuration and of differing lateral width; while they jointly serve to sustain cam pieces 20, in the form of stout flat-bar members longitudinally bent to approximately the arcuate curvature shown in Fig. I; that is to say, the major portion thereof is of parabolic profile with the ends 21, 22 of differential curvatures, for a purpose later on explained. Obviously, the cam pieces 20 are rigidly secured to the supports 17, 18 in spaced co-planar relation, and they are 35 adapted for engagement—as later on explained—by rollers 23, freely journaled on stub axles 24, in turn carried by appropriate bearings 25, securely attached to the rear wall of the skip-bucket 3, adjacent the sloping mouth 4, aforesaid.

Rigidly secured to the front of the track members 5 by means of angle-sections 26, are offset discharge rails 27; each of which is rounded at 28 and provided with an abutment 29 that serves to limit outward movement of the skip-bucket 3 anterior to dumping inclination, as well as disconnection of the wheels 6 from the tracks 5. These offset discharge rails 27 are, conveniently, arranged

vertically aligned co-planar to the inner edges of the track members 5 with their curved ends 28 swept into the lower ends of cut-outs or recessions 30 in the guide flanges of said rails. On the other hand, the portions 5 of the guide flanges adjoining the upper ends of the cut-outs or recessions 30 are upwardly and outwardly curved at 31 relative to the tracks 5 so as to offer no impediment to free 10 movement of the wheels 15, 6 and 7. Obviously suitable bracings—not shown—may be fitted in connection with the offset discharge rails 27 to rigidly sustain the same against lateral and other disalignment with respect 15 to the tracks 5.

In use, it will be apparent that, as the skip-bucket 3 is elevated, the rollers 23 will be brought into engagement with the cam pieces 20 by initial guidance of the lower curved 20 ends 22 thereof; while, incident to further elevation of said bucket, the leading wheels 6 thereon will emerge out of the cut-outs or recessions 30 in the tracks 5 by traversing the curved ends 28 of the discharge rails 27. Continued upward movement of the skip-bucket 3, incident to engagement of the rollers 23 with the cam pieces 20, progresses the wheels 6 along the discharge rails 27 until they impact the abutments 29 and are subsequently retracted (along with the skip-bucket 3 and bail members 12) to the position shown by dot-and-dash lines in Fig. I. Thus it will be readily understood that the axis 9 serves as the pivot about which the skip-bucket 3 is dumped; while the wheels 7 thereon never leave the tracks 5 during passage of the cut-outs 30 incident to the wheels 6 engaging the limiting abutments 29. Particular attention is also directed to the fact that any swinging movement of the skip-bucket 3 (other than that necessary for dumping) is effectively prevented by engagement of the straps or stops 16 with the bail members 12; or, in other words, the skip-bucket 3 is held—temporarily—stationary by means of the parts just recited and retainment of the wheels 15 and 7 in the tracks 5, above the cut-outs or recessions 30: all of which is easily visualized on an examination of Fig. I. Return of the skip-bucket 3 to re-filling location is so obvious from the foregoing description that it needs no detailed explanation herein.

The illustrated embodiment of my invention is simple to construct and operate; and, by reason of its simplicity, inexpensive to install and maintain: while the right is hereby reserved to make such detail changes as fairly lie within the scope of the appended claims.

Having thus described my invention, I claim:

1. In skip-bucket discharge mechanism of the type described, a skip-bucket with upper and lower pairs of wheels on common axes, 65 a suspension bail pivoted to the bucket bot-

tom intermediate the front and rear walls thereof and having a pair of similar wheels at its suspension end, a track with which all of said wheels normally engage in guiding travel of the bucket, said track having co-planar cut-outs affording entry to and exit from offset discharge rails each of which embodies a vertical abutment, a stationary offset arcuate cam path supported by the track, and a roller on the bucket co-operative with the cam path serving to move the bucket upper wheels from the track onto the discharge rails for impact with and retraction from the abutments aforesaid in effecting automatic inversion of the bucket incident to outward lateral displacement of its mouth relative to the track and limited turning movement about the axis of the lower pair of wheels thereon.

2. In skip-bucket discharge mechanism of the type described, a skip-bucket with upper and lower pairs of wheels on common axes, a suspension bail pivoted to the bucket bottom intermediate the front and rear walls thereof and having a pair of similar wheels at its suspension end, a track with which all of said wheels normally engage in guiding travel of the bucket, said track having co-planar cut-outs at the dumping level, paralleled offset arcuate stationary cam paths supported by the track with the ends thereof differentially curved, discharge rails sustained by the track communicating with the cut-outs therein, each said discharge rail having a rounded approach end and a relatively remote vertical abutment, and freely rotatable rollers on the bucket adapted to traverse the cam paths in effecting automatic outward displacement of the upper pairs of bucket wheels along the discharge rails for impact with and retraction from the abutments thereon and limited turning movement of said bucket about the axis of the lower wheels thereon.

In testimony whereof, I have hereunto signed my name at Philadelphia, Pennsylvania, this 3rd day of April, 1928.

ROBERT H. BEAUMONT.
